US0D1081698S

(12) **United States Design Patent** (10) Patent No.: **US D1,081,698 S**
 Clarke et al. (45) Date of Patent: ** Jul. 1, 2025

(54) **DISPLAY SCREEN OR PORTION THEREOF WITH GRAPHICAL USER INTERFACE**

(71) Applicant: **Foundry Innovation and Research 1, Ltd.**, Dublin (IE)

(72) Inventors: **Natasha Clarke**, Dublin (IE); **John Britton**, Dublin (IE); **Friedrich Wetterling**, Dublin (IE); **Michael Kelly**, Dublin (IE); **Fiachra Sweeney**, Dublin (IE)

(73) Assignee: **Foundry Innovation & Research 1, Ltd.**, Dublin (IE)

(**) Term: **15 Years**

(21) Appl. No.: **29/925,652**

(22) Filed: **Jan. 25, 2024**

Related U.S. Application Data

(63) Continuation of application No. 29/831,457, filed on Mar. 21, 2022, now Pat. No. Des. 1,015,348, which is a continuation of application No. 29/733,075, filed on Apr. 29, 2020, now Pat. No. Des. 946,622.
